UNITED STATES PATENT OFFICE.

WILLIAM EDGAR MIEDING, SR., OF NEW ORLEANS, LOUISIANA.

DESIGN FOR A PHONOGRAPH-CABINET.

58,924.

Specification for Design. **Patented Sept. 6, 1921.**

Application filed April 5, 1921. Serial No. 458,766. Term of patent 14 years.

To all whom it may concern:

Be it known that I, WILLIAM E. MIEDING, Sr., a citizen of the United States, residing at New Orleans, in the county of Orleans and State of Louisiana, have invented a new, original, and ornamental Design for a Phonograph-Cabinet, of which the following is a specification, reference being had to the accompanying drawing, forming part thereof.

Figure 1 is a front elevation of a phonograph cabinet, showing my new design.

Fig. 2 is a side elevation.

Fig. 3 is a top plan view.

I claim:

The ornamental design for a phonograph cabinet, as shown.

WILLIAM EDGAR MIEDING, SR.
